GEORGE W. EDWARDS'

UNITED STATES PATENT OFFICE.

GEORGE WILLIAM EDWARDS, OF FORT EDWARD, NEW YORK.

CONTROLLING DEVICE.

1,137,054.

Specification of Letters Patent. Patented Apr. 27, 1915.

Application filed July 27, 1914. Serial No. 853,377.

To all whom it may concern:

Be it known that I, GEORGE WILLIAM EDWARDS, a citizen of the United States, residing at Fort Edward, in the county of Washington and State of New York, have invented certain new and useful Improvements in Controlling Devices, of which the following is a specification, reference being had to the accompanying drawings.

10 This invention relates to new and useful improvements in controlling devices for engines, and has relation more particularly to a device of this general character especially adapted and designed for use with an engine 15 including a fly wheel, and the object of the invention is to provide a novel and improved device of this general character whereby the energy is under control of a device operable through the medium of the centrifugal action of the fly wheel.

The invention also consists of the details of construction, and the combination and arrangement of the several parts of my improved controlling device, whereby certain 25 advantages are obtained, and the device is rendered simpler, less expensive, and otherwise more convenient and advantageous for use, all as will be hereinafter more fully set forth.

30 The novel features of the invention will be carefully defined in the appended claims.

In order that my invention may be the better understood, I will now proceed to describe the same with reference to the accompanying drawings, wherein,

Figure 1 is a somewhat diagrammatic view, illustrating a controlling device constructed in accordance with an embodiment of my invention; Fig. 2 is an enlarged view 40 in elevation of the portion of the device, as herein embodied, adapted to be engaged with the fly wheel; and Fig. 3 is a view in end elevation of the device as illustrated in Fig. 2.

45 As disclosed in the accompanying drawing, E denotes an engine of the ordinary or approved construction but hereinafter shown as of stock type, and including a fly wheel W and the supply pipe P having interposed therein the controlling valve V.

Suitably connected to the fly wheel W and disposed radially thereof is the plate 1 secured thereto in any desired manner, but herein disclosed as anchored through the 50 medium of the bolts 2 through suitable openings produced in the plate and co-acting

with the fly wheel W. Adjacent the outer end, the plate 1 is provided with a sleeve 3 fixedly engaged therewith, and having the bore thereof threaded in order that the 60 barrel 4 may be adjustably engaged therewith for a purpose which will be hereinafter more fully set forth.

Loosely disposed through the barrel 4 is the elongated member 5 also disposed 65 through a guide loop 7 permanently secured to the plate 1.

The forward extremity of the elongated member 5 is normally held against movement with respect to the fly wheel W under 70 the influence of the expansible member 8 herein disclosed as a coil spring surrounding the said elongated member and having one extremity suitably engaged, as at 9, with a collar 10, fixed to the elongated member 5, 75 while the outer extremity of said expansible member 8 is suitably secured as at 11, to a sleeve 12, loosely mounted on the elongated member 5, and with which the inner extremity of the barrel is adapted to engage, 80 whereby it will be readily perceived that by imparting the requisite rotation to the barrel, the tension of the expansible member 8 may be regulated in accordance with the requirements of practice. Should it be the desire 85 to have the fly wheel rotate 123 R. P. M., the barrel 4 will be so adjusted as to create sufficient tension upon the expansible member 8 as to maintain the end-wise movable member 5 against outward movement under 90 the influence of the centrifugal force created by the rotation of the fly wheel W during the period that such rotation is 123 R. P. M. or less. As soon as the revolutions per minute become in excess of this predetermined number, it will be readily perceived 95 that the elongated member 5 will be caused automatically to move outwardly whereby the forward extremity thereof will operate the valve controlling mechanism, which will 100 now be described.

When in projected adjustment, the forward extremity of the elongated member 5 is adapted to engage an extremity of a lever 14 herein disclosed as pivotally supported 105 as at 15, intermediate of its length by the plate 16, said plate being adapted to be suitably anchored through any desired support, which may be used with convenience and facility. The opposite extremity of the lever 14 is provided with an opening 17 which is normally adapted to accommodate the up-

per extremity of the trip lever 18, herein disclosed as also pivotally connected, as at 19, intermediate of its length to the plate 15, hereinbefore referred to. The lower extremity of the trip lever 18 is formed into a laterally disposed finger 20 with which is adapted to be engaged a weighted member 21 of any ordinary or preferred construction. As herein disclosed, such member 21 is provided with an eye 22 through which the laterally directed projection 20 is adapted to be directed.

As is believed to be self-evident, it will be readily seen that as the projected extremity 15 of the elongated member 5 strikes the lever 14, the same will be disengaged from the trip lever 18, whereby the weighted member 21 will drop. Interposed within the supply pipe P adjacent to the controlling valve V, 20 is a valve B, with which is suitably connected a valve member 23 which is adjustable over suitable guides 24 and secured to the weighted member 21 or more particularly to the eye 26, formed with the eye 22, hereinbefore referred to. By this arrangement, it will be seen that as the weight 21 drops, the valve B will be adjusted into closed position and the engine brought to a stop.

From the foregoing description, it is 30 thought to be obvious that a controlling device constructed in accordance with the embodiment of my invention is of an extremely simple, durable and inexpensive nature and is particularly adapted for use by reason of the convenience and facility with which it performs its several functions, and it will 35 also be obvious that my invention is susceptible of some change and modification with-

out materially departing from the principles and spirit thereof, and for this reason 40 I do not wish to be understood as limiting myself to the precise arrangement and formation of the several parts herein shown in carrying out my invention in practice as defined in the appended claims. 45

What is claimed, is:

1. A device of the character described including a plate adapted to be secured to a rotatable element, alined loops carried thereby, one of said loops being interiorly 50 threaded, a barrel adjustably engaged with the threaded loop, a collar secured to the elongated member intermediate of the loops, a second collar loosely engaged with the elongated member intermediate the loops, 55 and an expansible member surrounding the elongated member and having the extremities thereof secured to the collars.

2. A device of the character described including alined loops adapted to be carried 60 by a rotatable element, one of said loops being interiorly threaded, a barrel adjustably engaged with the threaded loop, a collar secured to the elongated member intermediate of the loops, a second collar 65 loosely engaged with the elongated member intermediate the loops, and an expansible member surrounding the elongated member and interposed between and in contact with the collars.

In testimony whereof I hereunto affix my signature in the presence of two witnesses.

GEORGE WILLIAM EDWARDS.
